DESIGN FOR A MOTION PICTURE VIEWER

Warren C. Tichenor, Glendale, Calif.

Application November 23, 1936, Serial No. 66,104

Term of patent 7 years

To all whom it may concern:

Be it known that I, Warren C. Tichenor, a citizen of the United States, residing at 1957 E. Glen Oaks Boulevard, city of Glendale, in the county of Los Angeles and State of California, have invented a new, original, and ornamental Design for a Motion Picture Viewer, of which the following is a specification, reference being had to the accompanying drawing, forming part thereof, in which

Fig. 1 is a top view, Fig. 2 is a side view and Fig. 3 is a front view of a motion picture viewer, showing my new design.

I claim:

The ornamental design for a motion picture viewer as shown.

WARREN C. TICHENOR.
